UNITED STATES PATENT OFFICE.

GEORGE POTTER REED, OF MELROSE, MASSACHUSETTS.

WATCH-REGULATOR.

SPECIFICATION forming part of Letters Patent No. 311,609, dated February 3, 1885.

Application filed June 30, 1884. (No model.)

To all whom it may concern:

Be it known that I, GEORGE POTTER REED, a citizen of the United States, residing at Melrose, in the county of Middlesex and State of 5 Massachusetts, have invented certain new and useful Improvements in Watch-Regulators; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to "watch-regulators," so called, in which hitherto a toothed quadrant-rack engages a similarly-toothed pinion, and to the shaft of the latter is attached a star-wheel, whereby the movement 20 of the quadrant is effected and the watch regulated.

25 My invention consists in obviating the difficulties now existing in the use of a regulator made as above premised, and I employ in lieu thereof a segment of a circle and an actuating friction-roll with smooth peripheries, while the necessary friction between them to render the parts effective is obtained by employing a 30 spring-actuated shaft, upon which the friction-rod is mounted and by means of which a constant yet yielding contact is always maintained between the peripheries. The various operative parts of the regulator will be more fully hereinafter described.

35 The drawings accompanying this specification represent in Figure 1 a plan, and Fig. 2 a back view, of a regulator embodying my invention, while Fig. 3 is a cross-section of the quadrant and its roll, and Fig. 4 is a modified form of the bearing-surfaces.

40 In these drawings, A represents the balance-bridge, B the balance, and C the spring, of a watch containing my regulator. Upon that portion of the bridge inclosing the staff 45 of the balance I have fitted an annular ring, to which is attached the quadrant a. This quadrant, contrary to general usage, has a smooth periphery, as in the application of a regulator with a toothed quadrant and pinion 50 much difficulty has been found in obtaining the proper degree of interlocking. If too much, the two parts do not run smoothly and

their motion is slightly irregular; but if not sufficient, then lost motion ensues, either of which seriously affects the efficacy of the regulator. This periphery of the segment of a circle, a, is beveled, as shown at b, and coincides with a similar opposite bevel, c, cut on the friction-roll d, in order to obviate any tendency of the segment to ride up and thereby lessen the friction. An evident modification of this bevel, and one which is found very efficient, is to have the segment a V-shaped, to fit a corresponding V-shaped notch in the periphery of the friction-roll. As the segment is to be operated by friction alone with the friction-roll, it is necessary to have the latter spring-actuated, as a simple friction-roller would not suffice, owing to irregularities existing in the peripheries of the contact-surfaces, and at times it would be too tight or loose, as may be, and therefore useless. I have consequently cut a slot, e, in the balance-bridge somewhat larger than the friction-roll shaft f, to permit the latter to move freely 70 in any direction, and to obtain the requisite friction by maintaining the periphery of said friction-roll continuously in contact with that of the segment I have mounted the friction-roll shaft f in the extremity of a spring, g, attached to the under side of the balance-bridge. By this arrangement the tension of the spring maintains the friction-roll in constant but yielding contact with the periphery of the quadrant, and the strength of the spring may 75 be varied more or less, as is desired, while the shaft upon which the friction-roll is mounted is always carried in paths of movement at right angles to the surface of the balance-bridge.

90 Beneath the friction-roll and secured to the shaft f, I have placed the star-wheel D, and by movement of the latter rotation is imparted to the friction-roll and movement given to the quadrant in either direction, while, owing to 95 the yielding contact maintained by the spring, a minimum effect is produced upon the watch by the quadrant.

90 My invention is very simple, easily and cheaply constructed, and positive in its operation, while decidedly better results are obtained than by a regulator combining the toothed quadrant and pinion.

I do not desire to be limited to the particu-

lar form of peripheries herein shown of the quadrant and friction-roll, as the two may be sections of cylinders; but

What I consider as my invention, and desire to secure by Letters Patent, is—

In a watch-regulator, a balance-wheel, balance-spring lever, and toothless segment, in combination with a friction-roll which is in contact with said segment, and a spring which

automatically holds said roll against said segment, substantially as set forth.

In testimony whereof I affix my signature in presence of two witnesses.

GEORGE POTTER REED.
